ZERO RESETTING MECHANISM FOR REG-
ISTERSKarl Locke and Rudolf Brunhuber, Berlin-
Tempelhof, GermanyApplication June 5, 1935, Serial No. 24,996
In Germany August 2, 1934

14 Claims. (Cl. 235—144)

The present invention relates to improvements in zero-resetting mechanism for calculating or adding machines and the like, and more especially to calculating and similar machines having a counting mechanism with index-indicator wheels or rollers, arranged with parallel axes, on the shafts of which wheels or rollers, heartshaped clearing cams are provided which serve to set the counting indicators back to zero, thus to clear the machine.

Hitherto, in resetting mechanism of this kind, the heartshaped clearing cams, and with them, the index-indicator wheels are set back to zero by means of a sliding bar, which moves in a longitudinal direction of the counting mechanism. This method has the disadvantage that the initial resetting means for setting the clearing sliding bar into action, must be fixed to the carriage itself, because if attached to the rigid machine frame, the resetting or clearing operation is possible only when the slide is in a terminal position. A further disadvantage of this known arrangement is that the resetting or clearing slide has to move a comparatively extended distance and, being heavy, has considerable inertia and thus this load must be accelerated or retarded. This slows down operation and renders such an arrangement impracticable for machines with rapid action.

According to the present invention the resetting or clearing cams are not activated by a longitudinal motion of a bar, or the like, but by means of a rotary or oscillatory means set on an axis and located diagonally or across to the index wheel shafts. This means, in its preferred embodiment is in the form of levers, or in the form of sector arms, keyed to a joint horizontal shaft. The operation of these clearing levers or sector arms may be accomplished by turning their common shaft by hand, or by means of an operative rod or bar shiftably mounted on the machine frame, which in every tens carry-over position of the adding mechanism carriage stands opposite one of the clearing levers or sectors and whose function may be caused by direct pressure on an operative key or by coupling it to a lifter, driven by the motor of the machine.

In the drawing,

Fig. 1 represents a fragmentary cross-section of the counting mechanism carriage of an adding machine with two counting mechanisms, fitted in accordance with the new arrangement;

Fig. 2 shows a longitudinal section horizontally taken on line 1—1 of Fig. 1, looking in the direction of the arrows, and

Fig. 3 is a sectional view, taken on the line 3—3, Fig. 2, looking in the direction of the arrows.

In both views only such parts of the rigid machine frame are indicated as is necessary to a clear understanding of the invention, such parts serving for the support of key levers and to guide the operating rods.

The counting means carriage 1, Fig. 1, is slidably mounted on the rigid machine frame (not shown) by means of the slide rails 2 and 3. On said carriage are mounted two sets or groups of index wheel-shafts 4. Each of the index wheel-shafts 4 is provided in the known manner with an index wheel 5, a clearing cam 6, a tens carry-over lever 7 and a pinion 8, and each index wheel-shaft 4 is pivoted at its opposite ends 9 in the carriage plates 9' and 9''.

Along each group of the index wheel-shafts 4 and mounted transversely to said shafts is mounted within the counting means carriage a rockable clearing shaft 10, and on each of these shafts are fixed a plurality of spaced sector-shaped clearing levers 11, respectively cooperative with the clearing cams 6 to restore the index wheels to zero position, when the levers 11 are operated.

The sector-shaped levers 11 may be simultaneously operated by the reciprocation of the clearing bars 13 and 14, as will be explained below; and they may also be operated by manipulating a wing shaped lever 28, shown in dotted lines at the right of Fig. 2, which wing lever is fixed to one end of each of the shafts 10, so that the levers 11, may also be moved to restore cams 6 to their zero position, by an oscillation of shaft 10, through manipulation of the wing lever 28.

Near the handle 28, the shaft 10 carries fast thereon an arm 29, having a hooked outer end movable in an arcuate recess on the edge of the bearing plate 30. This hooked end is yieldably pressed into engagement with a stop face 27 of the plate 30 by means of a coil spring 26, on the shaft, having one end secured to the machine frame and the other engaged against the arm 29, thereby pressing the hooked end against the stop face 27 thereby yieldably holding the shaft 10 and levers 11 in their normal inactive position. The plate 30 also serves as a bearing for the shaft 10.

Slidably mounted in the machine frame are clearing bars 13 and 14 operative in substantially a vertical direction. At the upper end of each of the bars 13—14 is a roller 15 which strikes whichever clearing sector 11 is above it, when

the bar is lifted for clearing. The operation of the bar 13 is done by means of a key-lever 17, which is pivoted at 16 to the machine frame. The key-lever has at one end a key 18, while the other end is connected by a pivot 19 with the clearing bar 13. In this way the pressure on key 18 effects the clearing.

In case the back-to-zero cancellation is to be effected by a motor driven means, then, as indicated in Fig. 1 for the clearing bar 14, the key 20 carried on key lever 21, pivoted at 22, is connected to push-rod 23, the other end of which is connected to rod 14, by means of a slotted opening connection 24 and a trunnion 24'. By pressure on the key 20, the push rod 23 gets into the path of an operative extension 25a of a rotative cam 25, driven by the motor (not shown) of the machine, thus causing the lifting of rod 14 and thus operating clearing restoring means.

20 The manner of operating is as follows: The pinion shafts 4 are in random position after the adding operation. The clearing shafts 10 with their appurtenant clearing sectors 11 are in the starting position, indicated by full lines Fig. 1, 25 in which position they are held by the stop 27 and the spring 26. The clearing sectors 11 are outside of the path of the circle described by the high points of the clearing cams 6, during adding operation. When the shafts 10 are rotated in 30 the previously described manner, by lifting the rods 13 and 14, the individual sectors 11 act on the cancellation cams 6 to rotate them until they touch the flat portions of said cams thus causing their rotative restoration to zero, and leaving 35 them set in the zero position. After clearing, the shafts 10 are brought back to the initial, starting position by their springs 26. The edges of the clearing levers 11, where they contact with the clearing cams 6 preferably are sharpened.

40 It is to be noted that the rotation of the clearing shafts 10 may also be done by hand by means of a wing lever 28, Fig. 2, which is movable with and carried by the carriage.

We claim:

45 1. The combination in a calculating machine or the like, having a counting mechanism, including a plurality of parallel rotatable shafts having indicator wheels fixed thereon, comprising clearing cams on said shafts, and clearing means rockable about an axis adjacent and substantially transverse to the axis of said shafts and adapted to engage said clearing cams to restore said indicator wheels to their initial position.

2. The combination in a calculating machine 55 or the like having a counting mechanism, including a plurality of parallel rotatable shafts having indicator wheels fixed thereon, comprising clearing cams on said shafts and clearing means rockable about an axis located transverse 60 to the axis of said shafts and adapted by engaging said clearing cams to restore said indicator wheels to their initial position, said clearing means comprising a clearing shaft having mounted thereon a number of fixed clearing arms equal 65 in number to the number of said clearing cams, each of said clearing arms being adapted to engage a related one of said clearing cams.

3. The combination in a calculating machine 70 or the like, having a counting mechanism, including a plurality of parallel rotatable, spaced shafts having indicator wheels fixed thereon, comprising clearing cams fixed on said shafts, and spaced clearing means rockable about an axis adjacent and substantially transverse to the axis of said 75 shafts, said clearing means comprising a clearing

shaft having fixed thereto a number of clearing arms equal in number to the number of said clearing cams, said clearing arms being adapted to engage said clearing cams respectively, means for rocking said clearing shaft in one direction, and means on said clearing shaft for automatically restoring said clearing shaft in the opposite direction.

4. The combination in a calculating machine or the like, having a counting mechanism, including a plurality of parallel rotatable shafts having indicator wheels fixed thereon, comprising clearing cams fixed to said indicator wheel-shafts, a clearing shaft operatively mounted transverse to the axis of said indicator wheel-shafts, a plurality of sector discs rigidly connected to said clearing shaft and adapted to operatively engage said clearing cams, means to rock and stop said clearing shaft in one of its directions of rocking, means to automatically restore and stop said clearing shaft in the opposite direction of rocking, said automatic means comprising a movable spring actuated lever on said clearing shaft and key levers to move said sector discs.

5. In a calculating machine, a plurality of indicator-shafts each having a clearing cam thereon, the combination of a clearing shaft mounted for partial rotation; light weight thin clearing levers mounted fast on said clearing shaft, one for each indicator and each adapted, when the shaft is rocked slightly, to engage the associated clearing cam for restoring the indicator; the mass-acceleration of said shaft and levers being slight during rapid operation and requiring relatively small power.

6. In a machine comprising a frame, a carriage slidable thereon, and indicators on the carriage, the combination of means mounted on the carriage for restoring all of said indicators, said means including motive members traveling with the carriage when the latter travels; and operating means movably mounted on the frame and adapted to cooperate with one of said motive members at each of several positions of the carriage in its travel.

7. In a calculating machine comprising a non-traveling frame, a carriage slidable thereon and indicators in the carriage, the combination of means mounted on the carriage for restoring all of said indicators, said means including motive members spaced along the carriage; and non-traveling operating means movably mounted on the frame for movement perpendicular to the path of the carriage, and adapted to cooperate with one of said motive members whenever the carriage is in one of several positions.

8. In a calculating machine comprising a non-traveling frame, a carriage slidable thereon and indicators in the carriage, the combination of means mounted on the carriage for restoring all of said indicators, said means including motive members; and operating means movably mounted on the frame and adapted to cooperate with one of said motive members in each of several positions of the carriage, and adapted to operate the restoring means without danger of moving the carriage and interfering with the operation of the machine.

9. In a calculating machine comprising a machine frame, a carriage slidable thereon, a plurality of indicator-shafts each having a clearing cam thereon, the combination of a clearing shaft mounted on said carriage; clearing levers mounted fast on said clearing shaft, one for each indicator.

5 cator and each adapted, when the shaft is rocked, to engage the associated clearing cam for restoring the indicator; and a clearing bar mounted in the frame for movement toward an adjacent clearing lever and engageable with one of the clearing levers in each of several positions of the carriage.

10 10. In a calculating machine comprising a machine frame, a carriage slideable thereon, a plurality of indicator-shafts each having a clearing cam thereon, the combination of a clearing shaft mounted on said carriage parallel to the path of the carriage, and mounted on the carriage for partial rotation; clearing levers spaced along and mounted fast on said clearing shaft, one for each indicator and each adapted, when the shaft is rocked, to engage the associated clearing cam for restoring the indicator; a clearing bar slidably mounted in the frame for movement toward an adjacent clearing lever and having its upper end positioned to be engageable with one of the clearing levers only whenever the carriage is in one of several positions; and an operating lever engaging said bar for operating the same.

15 11. In a calculating machine comprising a machine frame, a carriage slideable thereon, a plurality of upright indicator-shafts each having a heart-shaped clearing cam thereon, the combination of a clearing shaft mounted on said carriage parallel to the path of the carriage and movable with the carriage when the carriage moves, and mounted on the carriage for partial rotation; sector-shaped clearing levers mounted fast on said clearing shaft, one for each indicator and each adapted, when the shaft is rocked, to engage the associated clearing cam for restoring the indicator; a clearing bar slidably mounted in the frame for movement, toward an adjacent clearing lever and having a roller on its upper end engageable with one of the clearing levers whenever the carriage is in one of several positions; an operating lever engaging said bar for operating the same; an operating cam; and

means for engaging the operating lever with the cam to operate such lever.

12. In a calculating machine, indicators; clearing means for restoring all of said indicators, said means including a motive member; a clearing bar slidably mounted for movement toward the motive member and having its upper end engageable with the motive member; an operating lever engaging said bar for operating the same; an operating cam; and means for engaging operating lever with the cam to operate the operating lever.

13. A device for simultaneously restoring the indicators of a machine having a plurality of indicator-shafts each having a clearing cam thereon, said device comprising a clearing shaft mounted for partial rotation; light weight clearing levers mounted fast on said clearing shaft, one for each indicator and each having its outer active end adapted, when the shaft is rocked slightly, to engage an associated clearing cam for restoring the indicator whereby all the indicators are simultaneously restored; the center of gravity of said levers moving only about half the distance of the movement of the active end, whereby the mass-acceleration of said shaft and levers is slight during rapid operation, requiring relatively small power.

14. A non-traveling device for simultaneously restoring the indicators of a machine comprising a stationary frame, a carriage slideable thereon, and a plurality of indicators on the carriage, said device comprising means adapted to be mounted on the carriage for simultaneously restoring all of said indicators, said means including motive members adapted to travel with the carriage when the latter travels; and non-traveling operating means adapted to be movably mounted on the frame and adapted to cooperate with one of said motive members at different positions of the carriage in its travel.
